UNITED STATES PATENT OFFICE.

JOHN SCOTT-TAGGART, OF ILFORD, ENGLAND, ASSIGNOR TO ALFRED ERNEST WHITE,
OF LONDON, ENGLAND.

AMPLIFYING SYSTEM.

Original application filed September 29, 1924, Serial No. 740,496. Divided and this application filed December 29, 1924. Serial No. 758,648.

To all whom it may concern:

Be it known that I, JOHN SCOTT-TAGGART, a subject of the King of Great Britain, residing at Ilford, in the county of Essex, England, have invented new and useful Improvements in and Relating to Amplifying Systems (for which I have filed an application in Great Britain, No. 217,971, dated January 2, 1923), of which the following is a specification.

This invention relates to amplifying systems, particularly for use in wireless telegraphy and telephony.

It is of general knowledge that when there are employed two or more stages of high-frequency amplification involving the use of two or more circuits tuned to the incoming frequency, and arranged so that each of two anode circuits has a tuned circuit associated with it either by coupling or direct connection, undesirable reactions or self-oscillations will very likely occur. This tendency toward undesirable reactions is due largely to capacity coupling in the valves themselves.

It has been proposed to counteract the tendency to self-oscillation of a single valve amplifier due to inherent capacity coupling between the electrodes of the valve by the use of a condenser connected so as to produce a reverse reaction effect, but when a plurality of stages of high-frequency amplification is involved, it has not hitherto been contemplated, so far as I am aware, that similar means could be successfully applied to said systems, owing to the relatively greater difficulties involved with each successive stage of amplification. I have found that by the suitable use of condensers connected to proper terminals of associated inductance coils in various stages, it is possible to neutralize this natural reaction effect and thereby insure the stability of the amplifier.

Accordingly, the invention in part consists of a high-frequency amplifier in which the currents are amplified by a plurality of stages of amplification involving a plurality of circuits, one or more condensers being connected so as to produce a reverse reaction effect to neutralize the tendency of the amplifier to generate oscillations.

A further feature of the invention con-

sists in a wireless receiver in which the incoming high-frequency currents are amplified by a plurality of valves in cascade coupled together, by the aid of circuits substantially tuned to the incoming frequency, and in which condensers are used, in the case of at least two valves, to feed back output currents of the valves to their respective input circuits so as to neutralize the natural reaction effects in the valves concerned.

The invention also provides an amplifying system using a thermionic valve in which the natural coupling capacity between the anode and the grid electrode and their respective circuits is supplemented by a condenser, another and distinct condenser being employed to balance out the reaction effects.

Other features of the invention and the methods for carrying the same into effect will be seen from a consideration of preferred embodiments of the same as disclosed in the accompanying drawings, and appended claims.

This application is a division of the application for United States Letters Patent 80 of John Scott-Taggart, Serial No. 740,496, filed September 29, 1924.

Fig. 1 represents a three-valve receiver in which two valves are utilized as high-frequency amplifiers coupled by tuned high-frequency transformers, the undesirable reaction effects due to the inter-electrode capacity coupling in the valves being neutralized by means of this invention.

Fig. 2 shows a circuit diagram of a three-valve receiver employing two stages of condenser-coupled high-frequency amplification with the present invention employed to balance out the undesired reaction effects due to the inter-electrode capacity coupling in the valves.

Referring to Fig. 1, it will be seen that the thermionic valves V_1 and V_2 serve as high frequency amplifiers, and the thermionic valves V_3 functions as a detector. 100 The antenna circuit L_1 and C_1 can be tuned to the incoming signal while the secondary inductance L_2 and the variable condenser C_2 serve to tune the input circuit of the thermionic valve V_1 in resonance with the 105 antenna circuit. The anode or output cir-

cuit of the valve V_1 includes a primary inductance L_3 shunted by a variable condenser C_5 by which the anode circuit may be tuned. Two other variable condensers 5 C_3 and C_4 connected in series with each other, are connected across the primary inductance L_3 and the variable condenser C_5 . The grid of the valve V_1 is connected to a point between variable condensers C_3 10 and C_4 while the high-tension battery B_2 is connected to the filament circuit of the valve V_1 and thence to a point on the primary inductance L_3 . The connection to the primary inductance L_3 need not be fixed, 15 but may be variably connected to any of the points intermediate the extremities of that coil. Condenser C_3 is a supplemental capacity connected across the grid electrode and the anode of valve V_1 in order to increase 20 the natural grid-to-anode capacity existing in valve V_1 , and between the circuits connected to these electrodes, in order that the resultant capacity may be increased to a practicable value. A discussion of the 25 operation of this supplemental capacity and a statement of the advantages to be derived therefrom will be found in the applicant's mentioned copending application.

The tuned circuit L_4 C_6 in the input or 30 grid circuit of the valve V_2 is coupled to the primary inductance L_3 of the output circuit of the valve V_1 . The anode or output circuit of the valve V_2 is tuned by means of the primary inductance L_5 shunted by 35 the variable condenser C_9 . The variable condensers C_7 and C_8 are connected across the terminals of the condenser C_9 of the primary inductance L_5 in the same manner as condensers C_3 and C_4 . The grid of the 40 valve V_2 is connected to a point between the condensers C_7 and C_8 . The valve V_2 in the same manner as the valve V_1 , has an anode circuit provided with an adjustable connection to the high tension battery B_2 , 45 by means of a variable tap engaging the windings of the inductance L_5 .

The input circuit of the detector valve 50 V_3 has a secondary inductance L_6 coupled to the inductance L_5 of the output circuit of the preceding valve and has a variable condenser C_{10} which functions to tune valve V_3 to the incoming signal. The usual grid condenser C_{11} shunted by a grid leak R_4 is provided in the grid or input circuit of 55 the detector valve V_3 , while the anode or output circuit of this valve includes the telephones T shunted by a bypass condenser C_{12} .

In the present arrangement the condenser 60 C_4 neutralizes any reaction currents which normally would flow through the coupling capacity existing between the anode and the grid electrode of the valve V_1 and the supplemental condenser C_3 , while the condenser C_8 neutralizes the capacity coupling existing 65 between the anode and grid electrode

of the valve V_2 and its supplemental condenser C_7 . It will be noted that the accumulator B_1 supplies the filaments of the valves with heating current through the rheostats R_1 , R_2 and R_3 . 70

Fig. 2 shows a modified circuit diagram of a receiver which is substantially similar to the circuit arrangement shown in Fig. 1 except that the various valves are coupled 75 capacitatively rather than inductively. The antenna circuit is tuned and the input circuit of the valve V_1 is likewise tuned, as in the preceding arrangement. The anode circuit of the valve V_1 includes inductance 80 L_1 and the high tension battery B_2 , while variable condenser C_{13} and inductance L_2 are connected in series around inductance 85 L_1 . The supplemental variable condenser C_2 is connected between the grid electrode and anode of valve V_1 to supplement the inter-electrode capacity existing between these elements and the circuits connected thereto, and the variable condenser C_1 has one terminal connected to a point between the variable condenser C_{13} and the inductance L_2 and has its other terminal connected to a conductor leading to the grid electrode of valve V_1 . Thus the variable 90 condenser C_2 supplements the inter-electrode capacity, while the variable condenser C_1 functions to neutralize any reaction currents which would otherwise pass through the inter-electrode capacity of valve V_1 and its supplemental condenser C_2 . The variable condenser C_5 and the resistance R_1 , 95 couple the output or anode circuit of valve V_1 to the input circuit of valve V_2 . The anode in the output circuit of the valve V_2 is associated with a net-work including a primary inductance L_3 , a secondary inductance L_4 , connected by means of a variable condenser in the same arrangement as the output circuit of the valve V_1 . In this instance also the variable condenser C_4 connected between the grid electrode and anode 100 of the valve V_2 supplements the inter-electrode capacity of this valve while the variable condenser C_3 is connected to the net-work last mentioned in such a manner as to neutralize any reaction effects due to the 105 inter-electrode capacity of the valve V_2 and its supplemental condenser C_4 . The fixed condenser C_6 and the resistance R_2 serve to connect the anode or output circuit of the valve V_2 to the grid of the detector 110 valve V_3 . The telephones T together with the high tension battery B_2 are connected in the anode circuit of this last mentioned valve. 115

While the high tension battery B_2 is connected to the midpoint of the inductance represented at L_1 L_2 and L_3 L_4 it will be understood that this connection may be made variable as in the arrangement shown in Fig. 1. 120 125 130

I claim:

1. In an amplifying system, a series of valves arranged in cascade, each valve being provided with a tuned input circuit and an output circuit, whereby inherent capacity coupling may exist, a condenser connected between the input circuit and the output circuit of each stage to supplement said inherent capacity, another condenser coupling adjacent stages, and means including other capacities for neutralizing said inherent capacities of said stages and said first-mentioned condensers.
2. In an amplifying system, a plurality of amplifying stages, each of said stages being provided with a tuned input circuit and a tuned output circuit whereby inherent capacity coupling may exist, a condenser connected between the input circuit and the output circuit of each stage to supplement the inherent capacity coupling, a condenser coupling adjacent stages, and means including other capacities for neutralizing said inherent capacities of said stages and said first-mentioned condensers.
3. In an amplifier, a valve provided with a filament, a grid electrode and an anode, a tuned input circuit connected between said filament and said grid electrode, a tuned output circuit connected between said filament and said anode, said output circuit including a network provided with an inductance, at least a portion of said inductance being connected between said anode and said filament, a condenser connected between said grid electrode and said anode, and a second condenser connected to said input circuit and to said inductance.
4. A high-frequency amplifier including a plurality of thermionic valves in cascade arrangement, each valve having a grid electrode and an anode, a grid circuit and an anode circuit, and an inductance coil connected in each anode circuit, one terminal of said coil being connected to the anode of its respective valve, an intermediate point of said coil being connected through a high-tension battery to the filament circuit, the other terminal of said coil being connected through a capacity to the grid electrode of the same valve and through another capacity to the grid circuit of the next succeeding valve.
5. A high-frequency amplifier including a plurality of thermionic valves in cascade arrangement, each valve having a grid electrode and an anode, a grid circuit and an anode circuit, an inductance coil in each anode circuit, one terminal of said inductance coil being connected to the anode of its respective valve, the midpoint of said coil being connected through a high-tension battery to the filament circuit, the other terminal being connected through a capacity to the grid electrode of the same valve and through another capacity to the grid circuit of the next succeeding valve, a condenser connected across the terminals of said coil and adjustable to tune the same, and a second condenser connected across the anode and the grid electrode of said first-mentioned valve to supplement the natural inter-electrode capacity thereof.
6. In a radio receiver, a series of thermionic valves in cascade arrangement, each of said thermionic valves being provided with a grid electrode and an anode, an input circuit terminating in each grid electrode, an out-put circuit terminating in each anode, a condenser connected between the input circuit and the out-put circuit of each valve to supplement the inherent capacity thereof, means for neutralizing said inherent capacities and the capacities of said first-mentioned condensers, a condenser coupling the out-put circuit of one thermionic valve to an input circuit of a second thermionic valve, a detector electrically associated with said second thermionic valve, said detector being provided with input and out-put circuits, and a condenser connecting the grid of one of said amplifying thermionic valves to the input circuit of said detector.

JOHN SCOTT-TAGGART.
